CLAIM

The ornamental design for a magnetic soldering tool clip, as shown and described.

DESCRIPTION

FIG. 1 is a perspective view of a magnetic soldering tool clip showing my new design;

FIG. 2 is a right side view thereof;

FIG. 3 is a left side view thereof;

FIG. 4 is a rear side view thereof;

FIG. 5 is a front side view thereof;

FIG. 6 is a top down plan view thereof; and,

FIG. 7 is a bottom up plan view thereof.

The stippling in the drawings represents texture and forms no part of the claimed design.
